(57) **CLAIM**

The ornamental design for a hat with hair, as shown and described.

DESCRIPTION

FIG. 1 is a perspective view of a hat with hair, showing my new design;

FIG. 2 is a front elevational view thereof;

FIG. 3 is a rear elevational view thereof;

FIG. 4 is a right side elevational view with the left side being a mirror image thereof;

FIG. 5 is a top plan view thereof; and,

FIG. 6 is a bottom plan view thereof.

The broken line showing of the word, "GirL" on the front portion of the band, the bows on the hair, as well as the small, circular shapes occurring across the crown, illustrates environmental matter and forms no part of the claimed design.

The narrow areas of crosshatching shown on the interior band on which the hair is attached in FIG. 1, although shown intermittently, are meant to represent woven fabric, and are understood to be distributed uniformly over the surface of the feature on which they reside.

The stippling shown in the drawings is for the purpose of shading, and forms no part of the claimed design.
